UNITED STATES PATENT OFFICE

GIOVANNI SPICA, OF VENICE, ITALY.

EXPLOSIVE AND METHOD OF MANUFACTURING SAME.

1,194,561.

Specification of Letters Patent. Patented Aug. 15, 1916.

No Drawing.

Application filed June 4, 1914. Serial No. 842,847.

To all whom it may concern:

Be it known that I, GIOVANNI SPICA, a subject of the King of Italy, residing at Venice, Italy, professor of chemistry, (whose post-office address is N°. 3341 Sant' Antônio, Venice, Italy,) have invented certain new and useful Improvements in Explosives and Methods of Manufacturing Same, of which the following is a specification.

- 10 In a memorandum published last year (*Atti del Reale Istituto Veneto di Scienze, Lettere ed Arti*, T. LXXI 1911/12, p. 782, and *Zeitschrift für das Gesamte Schieß- und Sprengstoffwesen*, 7 Jahrgang, 1/4 1912, 15 S. 129) the influence which phenanthrene could have in modern smokeless powder was disclosed, but as the results of further experiment it has now been found that phenanthrene can play under certain circumstances 20 a hitherto unsuspected rôle enabling improved processes of manufacture of gelatinized propellant explosives and improved explosives of this kind to be obtained.

As is well known in gelatinized nitrocellulose-nitroglycerin explosives, the nitroglycerin besides being an active ballistic component acts also as a solvent. In powders prepared with collodion cotton and with sufficient quantities of nitroglycerin, the 30 solvent action of the latter is sufficient (when appropriate methods are adopted) to give adequate gelatinization, but where the collodion cotton is replaced by guncotton the action of the nitroglycerin alone when 35 present in limited quantities is no longer sufficient to produce good gelatinization, as is also the case when collodion cotton is used with only a relatively small quantity of nitroglycerin. In these latter cases the gelatinization is promoted by a solvent such as 40 acetone which is added and which remains during the preparation of the powder, but is afterward as far as can be eliminated. As a consequence not only are traces of solvent necessarily left in the explosive causing 45 variation in composition and ballistic properties but the powder is obtained in a more or less porous condition harmful to its keeping qualities. Such procedure remains unaltered when stabilizing or cooling agents are used.

It has been ascertained that the introduction of phenanthrene into mixtures of nitro-

glycerin and collodion cotton can be effected in the following ways:—(a) by utilizing the property of the nitroglycerin to dissolve a certain proportion of phenanthrene at ordinary temperatures; (b) by the use of a phenanthrene solvent or of a solvent for the phenanthrene and the nitroglycerin or 55 collodion cotton, or both; (c) by mixing it directly with the pastes, utilizing in order to obtain homogeneity, its property of melting at a temperature of 96°-97° C. Under practical conditions however, the following 60 question arises:—The incorporation of the phenanthrene according to the first method besides presenting some danger in the dissolution when working with large quantities of nitroglycerin, has only a limited applicability as the phenanthrene is but slightly 65 soluble in the nitroglycerin at ordinary temperatures. This method is not, therefore, applicable in practice. The use of solvents according to the second method (b) has the 70 effect of yielding more or less porous powders, apt to favor chemical changes under external influences and therefore to reduce the life of the powder notwithstanding the 75 beneficial influence of the phenanthrene. 80 Taking into account this and other inconveniences hitherto encountered in powders prepared with solvents, this method also leaves much to be desired. This leaves the third method referred to which, in fact, has 85 now been found to be most satisfactory. As the result of careful experiments it has now been found that phenanthrene has the property while melting of acting as a solvent in nitrocellulose and nitroglycerin mixtures and 90 under the influence of warmth facilitates gelatinization and leads to satisfactory homogeneity in the product. As a result the employment of the stabilizer and cooling agent phenanthrene in such a way that it 95 can exert its gelatinizing action allows of obtaining a stabilized explosive with a low percentage of nitroglycerin and a high percentage of collodion cotton and without the employment of a volatile solvent.

The present invention consists in the manufacture of nitrocellulose-nitroglycerin explosives of this character by employment of phenanthrene under suitable conditions and in explosives so produced.

This invention further consists in the im-

proved methods and explosives hereinafter indicated.

The following are the proportions which have shown themselves the best. These are: 5 nitroglycerin from 28 to 32%, collodion cotton from 62 to 66%, phenanthrene from 5 to 7%. A remarkably good powder is obtained by the use of the following proportions:— nitroglycerin 29.96, collodion cotton 64.23, 10 phenanthrene 6.05, or in practice, nitroglycerin 30%, collodion cotton 64%, phenanthrene, 6%. The theoretical composition of this mixture and of its decomposition products are the following:—

The following method of preparation is the one which should be adopted for powders with the ingredients in proportion within the above limits: The phenanthrene is well mixed with the predetermined quantity of almost dry collodion cotton, and to this mixture, which is suspended in a water bath kept at 40° to 45° C. and continually stirred in every direction by a current of compressed air, is added, little by little, the appropriate quantity of nitroglycerin. When the latter has permeated the whole mixture, the bulk of the water is eliminated by filtration and the pasty mass allowed to stand at a temperature above 10° C. for 8 to 10 days. The paste is next centrifuged to free it from a further quantity of water and then it is submitted to compression between the cylinders of a sheeting machine, which are internally heated by steam so as to reach at the external surface a temperature of 100° to 105° C. The repeated flattening increases the density, eliminates the water, melts the phenanthrene and completes the gelatinization of the product, which is thus obtained as homogeneous, dry, transparent sheets devoid of blisters and of light color. 45 These sheets kept at the thickness required, are while still somewhat warm cut by a special cutter into strips of the desired size for arms of different caliber. The powders thus prepared are similar to ballistite, but 50 are a little lighter in color and also a little more horny.

The composition specified above gives a powder with a density of 1.6. This one, which, according to calculation, for each 55 kilogram should yield 1014 liters of gas and liberate 866 calories, has given when exploded in the Berthelot bomb 864 calories. No trace of nitric acid could be found. Exploded in the Vielle bomb in such quantity 60 as to give an internal pressure of 2500 atmospheres, a corrosion value of 0.036 per gram was obtained. A stability test at a temperature of 80° C. in the silvered vessel showed an average of 2800 hours, while

shooting tests have demonstrated the greatest regularity in ballistic effects.

In order that the above data may be contrasted with results upon other gelatinized explosives the following table is given:—

kind of explosive.	Absolute density.	Calories developed from 1 kg. powder.	Liters of gas at 6° C. and at 760 mm. given by 1 kg. powder.	Corrosive powder per gram.	Durability (silvered test) in hours.	Observations.	75
Ballistite (50% of nitroglycerin).	1.63	1250	810	0.169	150	Made without solvent.	
Cordite M. D. (30% of nitroglycerin).	1.57	970	948	.....	930	Made with solvent.	80
"Chilworth" powder.	1.55	889	964	0.063	2500	Made with solvent.	
Powder above described.	1.60	864	1014	0.036	2800

The principal advantage of the improved methods and products according to this invention are it will be understood, as follows:—(1) The explosives can be conveniently manufactured without the help of volatile solvents and are quickly in condition for use. (2) They have a constant and definite composition and give ballistic effects of the greatest regularity. (3) They develop in explosion a small amount of heat. (4) That in explosion an extremely large volume of gases is generated. (5) That there is no nitric acid among the products of explosion. (6) That corrosion in arm or weapon is reduced to a minimum. (7) That an extremely high figure is obtained in the durability test at 80° C. in the silvered vessel. To this may be added the economic advantage, arising from the cost of manufacture of such powders being lower than that of powders manufactured with a volatile solvent.

Having now fully described my said invention and the manner in which the same is to be performed, what I claim and desire to be secured by Letters Patent of the United States is:

1. In the manufacture of smokeless powders of the character described, the herein described method which consists in mixing phenanthrene with a predetermined quantity of collodion cotton and putting the mass in a water bath kept at a temperature of from 40° to 45° C., stirring the mixture with the water while adding gradually a quantity of nitroglycerin, then removing the excess of the water by filtration and allowing the still pasty mass to dry at a temperature above 10° C., then centrifuging the dried pasty mass to free it as much as possible from the rest of the water, and then compressing the mass by means of cylinders which are mean-

while heated from the inside by means of steam, as set forth.

2. A smokeless powder of the character described consisting essentially of collodion 5 cotton, nitroglycerin and phenanthrene in or about in the proportions specified.

In testimony whereof I have signed my

name to this specification in presence of two subscribing witnesses.
